Attorneys

UNITED STATES PATENT OFFICE.

CHARLES H. GREENAWALT, OF LIMA, OHIO.

ICE PACKER.

Application filed September 13, 1922. Serial No. 588,095.

To all whom it may concern:

Be it known that I, CHARLES H. GREENAWALT, a citizen of the United States, and a resident of Lima, in the county of Allen 5 and State of Ohio, have invented certain new and useful Improvements in Ice Packers, of which the following is a full, clear, and exact description.

My invention relates to ice packers, and 10 one of the objects of the invention is to provide a device of this character which will not only quickly perform the operation of packing ice cream, but will do so in such a manner that the ice will be forced into such 15 a compact mass that the small lumps of ice will actually freeze together, so that the consumption of ice is obviously greatly reduced.

Another object of the invention is to provide a device of this character which is ar- 20 cuate in general outline, so that it will enter the space between the ice cream container and the packing tub or cabinet, extend partly around the ice cream container, and fit snugly about the container, so that in the 25 operation of the implement it is assured that the ice adjacent to the ice cream container will be thoroughly packed.

Another object of the invention resides in the provision of a device of this character 30 which is so constructed that it will be impossible for any relatively sharp points or edges to strike either the ice cream container or the tub, which in the prior practice are often damaged in this manner.

Still other objects and advantages of the 35 invention reside in the provision of a device of this character which is most simple in construction, inexpensive in manufacture, and practically indestructible in operation.

Other and further advantages of this in- 40 vention will be apparent from the following detailed description when taken in connection with the accompanying drawings; in which,

Figure 1 is a perspective view of the 45 packer, the handle portion being broken away.

Figure 2 is a vertical sectional view show- 50 ing the manner in which the handle portion is attached to the head.

Figure 3 is a vertical section showing the 55 apertures through the head.

Figure 4 is an elevation of the tub, 60 container, and ice packer, the tub being broken away to show the interior; and,

Figure 5 is a horizontal sectional view taken on line 5—5 of Figure 4.

Referring to the drawings more in detail, 65 numeral 1 indicates a conventional ice cream tub or cabinet. The tub illustrated is circular in cross section, but of course a tub or cabinet of any shape may be employed.

The usual ice cream container 2 is ar- 70 ranged in the tub, and the space between the wall of the tub and the wall of the container is filled with ice. It is well known 75 that this ice must be packed at intervals, and the amount of ice consumption depends to a large extent on how well the packing operation is performed. In the prior prac- 70 tice various crude implements have been used to pack the ice, and while they pack it to some extent, yet it is done in a most in- 75 efficient manner, for the implements now used dig holes into the mass of ice while it is being packed, and obviously this increases the ice consumption instead of de- 80 creasing it. In the operation of the present invention the ice is quickly packed into a mass so compact that the lumps actually 80 freeze together. I will now describe the specific construction of the ice packer or tamper which produces these highly de- 85 sirable results.

The packer or tamper comprises a head 85 indicated by numeral 3, and a handle por- 90 tion indicated by numeral 4. The head 3 is arcuate in general outline and is shaped to fit into the space between the tub and the ice cream container, to substantially con- 95 form to the curvature of the ice cream container, and to extend partly around the same. This is one of the important features of the invention, that the inner edge of the head of the packer substantially conforms 95 to the shape of the ice cream container.

The outer edge of the packer is also curved in the preferred construction of the device, but it is not essential to the successful 100 operation of the device. The ends of the head are not formed into points but are cut off short, so that the ends are flattened for a considerable length, as indicated by numeral 5. If the head ended in points it would be 105 possible to damage the tub and ice cream container if the packer should be carelessly operated. But in the construction just de- 110 scribed it is impossible to injure either the tub or the ice cream container, for there is only a limited space between the packer and

the walls of the tub and container, and hence the lateral movement of the packer is limited, so that it would be impossible to rotate the packer sufficiently to bring any 5 of the corners thereof into contact with either the tub or container.

Of course the handle portion may be attached to the head in any desired manner, but I have illustrated a construction in 10 which the head is provided with a recess 6, the wall of which is screw-threaded; and the handle portion 4, which may be any ordinary pipe section, is adapted to screw-threadedly engage in said recess.

15 While it is not an essential feature of the invention, I prefer to provide the head with two or more apertures, indicated by numeral 7, through which water is allowed to pass as the ice is packed.

20 In the packing operation a series of blows are delivered by the packer, and as the implement covers considerable area the operation is quickly performed. But more important than the saving of time in the operation 25 is the saving of ice which is accomplished by efficient packing. By the use of the implement described herein, all of the ice is packed into an extremely compact mass, this being especially true of the ice adjacent to the ice cream container, and on account of the size and shape of the implement no holes are formed in the ice mass. As previously stated, when ice is packed 30 with my implement it will be formed into such a compact mass that the lumps will actually freeze together, and obviously when ice is forced into such a compact mass the saving in the ice consumption will be very great, and it will have to be packed less 35 frequently.

40 It will also be understood from the foregoing description that the packer head is so formed that it will be impossible for any

relatively sharp points or edges to strike the tub or ice cream container.

45

The head of the packer may be made of any desired material, but it will preferably be made of cast iron, and it may be cast hollow or otherwise, the essential feature thereof being that the head must have the 50 inner edge thereof curved to conform in a general way to the curvature of the ice cream container.

The bottom of the head may be corrugated if preferred, but as this forms no part of the 55 invention, it is not necessary to illustrate such a construction.

In accordance with the patent statutes I have described what I now believe to be the best embodiment of my invention, but I do 60 not wish to be understood thereby as limiting myself or the scope of my invention, as many modifications may be made without departing from the spirit of the invention, and all such I aim to include in the scope 65 of the appended claim.

What I claim as new and desire to secure by Letters Patent is:

A hand implement for packing ice between an ice cream container and its tub, 70 said implement comprising a head and a handle portion attached thereto, said head having an aperture extending therethrough for the passage of water, the head constructed to extend part way around the ice 75 cream container, the inner edge of the head being curved to conform substantially to the curvature of the ice cream container, the ends of the head being flattened, and there being a relatively small clearance between 80 the head and the walls of the tub and ice cream container, whereby it is impossible to rotate the packer sufficiently to bring the corners thereof into contact with either the tub or the container.

CHARLES H. GREENAWALT.
